UNITED STATES PATENT OFFICE.

NATHANIEL B. POST, OF CHICAGO, ILLINOIS, ASSIGNOR TO POST MACHINE CO., OF CHICAGO, ILLINOIS, A CORPORATION OF ILLINOIS.

CORN-POPPING MACHINE.

1,251,279.

Specification of Letters Patent. Patented Dec. 25, 1917.

Application filed November 19, 1914. Serial No. 873,027.

To all whom it may concern:

Be it known that I, NATHANIEL B. Post, a citizen of the United States, and a resident of the city of Chicago, county of Cook, and 5 State of Illinois, have invented certain new and useful Improvements in Corn-Popping Machines, of which the following is a specification.

My invention relates to corn popping machines and the object of this improvement is to provide a simple and effective device of the character mentioned which is adapted to display the corn during the process of popping.

15 Other objects will appear hereinafter.

The invention consists in the combinations and arrangements of parts hereinafter described and claimed.

The invention will be best understood by 20 reference to the accompanying drawings forming a part of this specification, and in which,

Figure 1 is a plan view of a corn popping machine embodying my invention,

25 Fig. 2 is a central longitudinal section of the same,

Fig. 3 is a central transverse section of the same,

30 Fig. 4 is a section taken on line 4—4 in Fig. 2,

Fig. 5 is a fragmental elevation of a portion of the upper side of the machine,

Fig. 6 is a section taken on line 6—6 in Fig. 2,

35 Fig. 7 is an enlarged section taken on line 7—7 in Fig. 5, and

Fig. 8 is a fragmental section of the feeding mechanism.

My device is designed so that a number of 40 popping elements may be incorporated in one case, and operated either independently or together. In the form shown, I have embodied two separate popping elements, and when so desired, I may use more or less than 45 two popping elements, as will be readily understood. Both of the popping elements are similar in form and construction, and a description of one will suffice for both. The device consists of a case 8 of any desired 50 shape and size and is preferably made up having plate glass sides in order to expose the mechanism of the device and display the corn during the process of popping. The top 9 of the device is preferably of metal

and provided with bosses 10 on its under 55 side. Secured in the bosses 10 are a plurality of depending rod supports 11. On said rod supports 11 is supported a popping plate 12, the popping plate having ears 13, see Fig. 1, which are adjustably secured to the 60 rods in order to support the popping plate in fixed position. Since the popping plate is stationary or fixed in position it can be readily provided with an electrical-heating coil as shown. This method of heating the 65 plate is preferred because it is less dangerous than gas or the like, although gas may be used by placing a suitable burner under the plate, if desired.

On the upper side of top 9 of the casing 70 are provided bearings 14 supporting a main driving shaft 15, the latter being driven by a belt 16 connected with a suitable source of power, not shown. On the shaft 15 is fixed a bevel gear 17 meshing with a second 75 bevel gear 18, the latter being fixed on a shaft 19 which extends downwardly, and has its lower end journaled in a suitable recess 20 in the popping plate. Secured on the lower end portion of shaft 19 is a conically 80 shaped hub 21 having a pin connection with shaft 19. Secured to the bottom of hub 21 are agitator fingers 22, the latter being secured to hub 21 by means of rivets, or their equivalent. The fingers 22 are disposed in 85 lines, substantially tangent to said hub, or in lines extending rearward of radiating lines from said hub, the particular position of the fingers being adapted to facilitate removing corn from the popping plate during 90 the process of removing the popped corn from said plate 12. The ends of the fingers 22 extend over the lateral edge of popping plate 12 in order to be sure to remove the corn from the edges of such plate during 95 the process of emptying said plate.

Mounted above plate 12 is a cover 23 having its hub 24 slidably mounted on shaft 19. The top of cover 23 is provided with lateral flanges 25 which rest on arms 26 adjustably secured to supporting rods 11 in order to support the cover in its lower position. The arms 26 are so spaced on rods 11 that the lower edge of cover 23 will be sufficiently high from plate 12 to permit of 100 the operation of the fingers 22 between said plate and cover. The cover is spaced sufficiently low to prevent corn from passing 105

between the plate and cover, as will be readily understood. Secured to the hub 24 of said cover and extending upwardly through the top 9 are two connecting links 27 which 5 are connected at their top ends with a lever 28, the latter being pivoted to an ear 29 on the top of plate 9 so that upon upward movement of said lever, said cover 23 will be raised from its full line to its dotted line 10 position as indicated at the left hand side in Fig. 2.

A shaft 30 is mounted in suitable bearings and disposed transversely of top 9. A worm and worm gear connection 31 are provided 15 between shaft 15 and shaft 30 in order to drive the latter. The shaft 30 carries a cam 32 which coöperates with cam members 33 secured to a connecting link 34. In the device as illustrated where two popping elements are employed, the connecting link 34 20 operates both elements, as clearly shown. The end of connecting link 34 is pivoted to the outer end of an arm 35 which carries a dog 36 coöperating with a ratchet wheel 37 secured on a shaft 38, the latter being mounted 25 in suitable bearings carried on top 9. The shaft 38 carries a rigidly secured cam 39 which coöperates with a cam member 40 secured on lever 28, so that when shaft 38 30 is rotated, cam 39 will engage cam member 40 and raise lever 28 to cause raising of cover 23.

Mounted above the top 9 is a hopper 41 which is adapted to carry the unpopped 35 corn. Said hopper is mounted on two upwardly extending ribs or sides 42 which are parallel with each other. In the opening formed between the two parallel sides 42 and the bottom of hopper 41 and top 9 is 40 reciprocally mounted a plunger 43. The plunger 43 is provided with a perforation 44 and the latter is adapted to alternately coöperate with a suitable opening in top 9 and one in hopper 41 to feed corn from said 45 hopper through said top upon reciprocation of the plunger 43. On shaft 30 is a crank arm 45 which is connected by means of a connecting link 46 with the plunger 43 to cause reciprocation of the latter. The plunger 43 is made up of an end member 47 50 which is connected to the link 46, and two side plates 48 which are rigidly connected to said end 47. The other ends of side plates 48 are bent toward each other and off-set, 55 the off-set portions being adapted to receive a flange nut 49 which is threaded on a screw rod 50 carried by the movable end 51 of said plunger. The nut 49 is provided with a wire handle 52 to facilitate turning the 60 same. The arrangement is such, that upon turning nut 49, movable end 51 will be moved longitudinally of plates 48 to increase or decrease the size of opening 42 in said plunger. Varying the size of the 65 opening 44 in the plunger provides a means

for feeding a greater or less quantity of corn at each reciprocation of the plunger, as will be readily understood.

Immediately below the opening in top 9 which coöperates with plunger 43 is a reservoir 53, the lower end of the latter being restricted and provided with a downwardly swinging door 54. Said door is normally held closed by means of a spring 55, as will be readily understood. Secured to the door 75 54 is an arm 56 extending upwardly and connected by means of a connecting link 57 with a lever 58, the latter being pivoted as at 59 to the reservoir 53 and extending upwardly through a suitable slot in top 9. On shaft 38 is a cam 60 adapted to coöperate with the upper end of lever 58 to cause rocking of the door 54 downwardly to permit emptying the reservoir 53. The arrangement is such, that at each revolution 85 of shaft 30, crank arm 45 will cause the reciprocation of plunger 43 thereby dropping a quantity of corn from hopper 41, corresponding to opening 44, into reservoir 53. The ratio of rotation of shafts 38 and 30 90 correspond to the number of teeth on ratchet wheel 37, and upon each rotation of shaft 38, the cam 39 will cause cover 23 to be raised and as soon as said cam 39 passes cam member 40, the cover will be dropped 95 and as soon as such cover is dropped, cam 60 engages the upper end of lever 58 causing door 54 to be opened, permitting the corn in said reservoir to be dropped onto plate 12 through a suitable opening in cover 100 23. The number of quantities of corn which are fed by plunger 43 to the hopper, correspond to the number of teeth on ratchet wheel 37, as will be readily understood.

Positioned under popping plate 12 and 105 mounted in lugs 61 is a funnel-shaped member 62 open at its bottom and adapted to convey the corn which is discharged from plate 12 downwardly to a separating member. The separating member comprises a 110 plurality of spaced rods 63 spaced sufficiently far apart to prevent the popped corn from passing through them and to permit the unpopped corn to pass therethrough. Under the bars 63 is a discharge hopper 64 115 provided with a discharge pipe 65 and is adapted to receive the unpopped corn passing through said bars and convey such unpopped corn through the bottom of the machine. Mounted under the bars 63 are bars 66, the latter carrying upwardly extending pointed fingers 67 which are adapted to pass between the bars 63 in order to move corn deposited on said bars toward the flavoring part of the device. The bars 66 120 are mounted on crank arms 68 and the latter are connected together by means of cranks 69 and link 69' to cause the uniform movement of said crank arms, the cranks 69 being positioned at right angles to cranks 125 69' 130

68 so that there can be no dead center. The arrangement is such, that upon crank arms 68 revolving, the points 67 will be moved in one direction when extending above rods 63 5 and in the reverse direction when under said rods, thereby moving the corn on said rods 63 only in one direction. One of the crank arms 68 is connected by means of spur gears 70 with a stud shaft 71, the latter being connected by means of a chain and sprocket 72 with shaft 30, see Fig. 3. In constructing a machine having two popping elements, it is advantageous to bring the corn from both elements to a common flavoring element. In order to accomplish this, I connect one of the elements adapted to move the corn on bars 63 with spur gears 70, as described, and the other of said moving elements with a sprocket and chain connection 73, see Fig. 6. This arrangement causes the corn from both popping elements to be deposited in the same flavoring element.

Secured between the two sets of rods 63 25 is a trough 74 having a well 75 at its bottom for containing a flavoring substance such as melted butter, said trough being removably secured to the bottom of certain of the depending supports 11, as clearly indicated in Fig. 2. Mounted in the well 75 is a spool-shaped member 76 carried by a shaft 78 connected by means of a chain and sprocket 79 with a counter-shaft 80, the latter being connected to one of the crank arms 30 68 by means of bevel gears 81. The trough 74 is provided with inwardly extending guide flanges or lips 77 and 77' passing between the flanges of spool member 76, as indicated in Fig. 6, said flanges being provided for the purpose of guiding the pop corn to and from said spool member. A shaft 82 is mounted immediately above trough 74 and is provided with arms 84 which pass between the flanges of spool member 76 and move the corn from said spool member through the outer end 85 of the trough 74 to deposit the same at the bottom of case 8, a result which is assisted by the rotation of spool 76. By this arrangement, the corn is supplied with the flavoring by contact with the flanges and spindle of said spool member, as will be readily understood.

In operation the plunger 43 is reciprocated to move several measured quantities of the unpopped corn into the reservoir 53, where it is preheated before being delivered into the popping plate. When the cover 23 is lowered, the door or gate 54 is opened and the several measured quantities of unpopped corn in the reservoir 53 fall onto the popping plate. The popping plate is rimless throughout its periphery but the vertically movable cover has a continuous rim of substantially the same size as the plate so that,

when it is in lowered position, it prevents the escape of corn from the surface of the plate during the popping operation. During the popping operation arms 22 agitate the corn and also tend to move the unpopped corn outwardly over the surface of the plate toward its periphery.

In order to preserve the freshness of popped corn it is highly desirable to remove it as quickly as possible from contact with the hot popping surface. In the present construction as soon as the cover is raised, the popped corn is quickly discharged, not from one portion only of the periphery, but from substantially all portions thereof and passes into the funnel 62 which is of sufficient size to receive the corn from all portions of the periphery of the rimless popping plate. Furthermore, by extending the agitating arms to the edge of the rimless popping plate a quick discharge of the corn is facilitated and all of the corn is discharged therefrom so that it cannot interfere with the proper closing movement of the cover.

The popping element of the device is adapted for use in roasting peanuts, coffee or the like, when so desired, by raising pawl 36 out of engagement with ratchet wheel 37 to arrest the movement of shaft 38 and cams 39 and 60, thereby preventing the raising the cover 23 and operation of the feeding element at their regular intervals, as described above. When the roasting operation has continued for the required time, 100 cover 23 may be manually raised or pawl 36 returned to engagement with its ratchet wheel 37 to restore the cover 23 and feeding element to their regular operations.

While I have illustrated and described the preferred form of construction for carrying my invention into effect, this is capable of variation and modification without departing from the spirit of the invention. I, therefore, do not wish to be limited to the 105 precise details of construction set forth, but desire to avail myself of such variations and modifications as come within the scope of the appended claims.

Having described my invention what I 115 claim as new and desire to secure by Letters Patent is:

1. In a corn popping machine, the combination of a popping plate rimless substantially throughout its periphery, a cover for holding the corn in position on said plate, agitating means for moving the corn outwardly toward the periphery of said plate and means for relatively shifting said cover and said plate to permit the simultaneous discharge of the popped corn from substantially all portions of the periphery of said plate by said agitating means.

2. In a corn popping machine, the combination of a rimless popping plate, a cover

of substantially the same size as said plate for holding the corn in position thereon, a rotary agitator upon the upper surface of said plate for moving the corn outwardly 5 toward the periphery thereof and means for raising said cover to permit the simultaneous discharge of the popped corn from substantially all portions of the periphery of said plate by said rotary agitator.

10 3. In a corn popping machine, the combination of a stationary circular popping plate rimless substantially throughout its periphery, a movable cover having a rim for holding the corn in position on said 15 popping plate, agitating means for moving the corn outwardly toward the periphery of said plate and means for lifting said cover to permit the simultaneous discharge of the popped corn from substantially all 20 portions of the periphery of said plate by said agitating means.

4. In a corn popping machine, the combination of a stationary popping plate rimless throughout its periphery, a bodily movable 25 cover having a continuous rim for holding the corn in position upon said popping plate and a rotary agitator having a series of arms extending over the surface of said plate at least to the periphery thereof and 30 arranged to discharge the popped corn from substantially all portions of the periphery of the plate when the cover is raised.

5. In a corn popping machine, the combination of a stationary popping plate; a vertical shaft mounted above the center of said plate; a hub fixed on the lower end portion of said shaft; agitator arms secured to said hub and resting on and having their ends extending over the peripheral edge of said 40 plate, said arms being disposed in lines at angles to and rearward of lines radiating from their inner ends; and a cover over said plate and having its lower edge spaced above the latter providing a slot for the 45 movement of the ends of said agitator arms, substantially as described.

6. In a corn popping machine, the combination of a support; a popping plate having a bearing in its upper side; a vertical shaft 50 having its lower end journaled in said bearing; an agitator fixed on said shaft and having arms extending over the peripheral edge of said plate; a cover over said plate and having a peripheral flange thereon; and 55 arms on said support engaging said flange and spacing said cover above said plate permitting movement of the outer ends of said agitator between said cover and said plate, substantially as described.

60 7. In a corn popping machine, the combination of a plate rimless throughout its periphery, a bodily movable cover having a continuous rim for holding the corn in position on said plate, means for feeding corn 65 onto said plate through said bodily movable

cover, mechanism for alternately operating said feeding means and said cover, agitating means operating over the surface of said plate and arranged to discharge the corn from substantially all portions of the periphery thereof when the cover is raised and a shaft extending through said bodily movable cover for operating said agitating means.

75 8. In a corn popping machine, the combination of a popping plate rimless substantially throughout its periphery, a cover for holding the corn in position on said plate, agitating means for moving the corn outwardly toward the periphery of said plate, 80 means for lifting said cover to permit the simultaneous discharge of the popped corn from substantially all portions of the periphery of said plate by said agitating means and means for collecting the corn 85 as it is discharged from said plate.

9. In a corn popping machine, the combination of a frame; a popping plate supported in said frame; a cover over said plate and adapted to slide vertically; a lever pivoted on said frame; connecting links connecting said cover with said lever; a shaft journaled in said frame; and a cam on said shaft adapted to engage said lever and raise said cover vertically from said plate, substantially as described.

10. In a corn popping machine, the combination of a frame; a popping plate supported in said frame; a cover over said plate and adapted to slide vertically; a lever pivoted on said frame; connecting links connecting said cover with said lever; a shaft journaled in said frame; a cam on said shaft adapted to engage said lever and raise said cover vertically from said plate; and means 100 operatively connected with said shaft and adapted to remove corn from said plate while said cover is raised, substantially as described.

11. In a corn popping machine, the combination of a popping element; a plurality of stationary bars under said popping element and adapted to receive corn therefrom, said bars being spaced apart to permit the passage of unpopped corn but sufficiently close to prevent popped corn from passing therebetween; and means for moving the popped corn longitudinally of said bars, substantially as described.

115 12. In a corn popping machine, the combination of a popping element; a plurality of stationary bars under said popping element and adapted to receive corn therefrom, said bars being spaced apart to permit the passage of unpopped corn but sufficiently close to prevent popped corn from passing therebetween; and fingers between said bars, mounted to move longitudinally thereof and adapted to move corn from said bars, substantially as described.

13. In a corn popping machine, the combination of a popping element; a plurality of stationary bars under said popping element and adapted to receive corn therefrom, 5 said bars being spaced apart to permit the passage of unpopped corn but sufficiently close to prevent popped corn from passing therebetween; means for moving the popped corn longitudinally of said bars; and a collecting member under said bars adapted to receive unpopped corn passing through said bars, substantially as described.

14. In a corn popping machine, the combination of a popping element; a flavoring trough; and a spool-shaped member rotatably mounted in said trough and adapted to engage corn discharged from said popping element, substantially as described.

15. In a corn popping machine, the combination of a popping element; a flavoring trough; a spool-shaped member rotatably mounted in said trough and adapted to engage corn discharged from said popping element; and rotating fingers passing between 25 the flanges of said spool-shaped member and adapted to remove corn from the latter, substantially as described.

16. In a corn popping machine, the combination of a popping element, a plurality of 30 stationary bars adapted to receive corn from said popping element, said bars being spaced apart to permit the passage of unpopped corn but sufficiently close to prevent popped corn from passing therebetween and means for moving the popped corn longitudinally of said bars.

17. In a corn popping machine, the combination of a popping plate, a plurality of bars adapted to receive corn therefrom, said 40 bars being spaced apart to permit the passage of unpopped corn but sufficiently close to prevent popped corn from passing therebetween and agitating fingers movable upwardly and forwardly between said bars for moving the popped corn longitudinally thereof and for discharging the same therefrom.

18. In a corn popping machine, the combination of a horizontal popping plate, a

plurality of substantially horizontal bars, 50 means for moving the corn from said plate onto said bars, the latter being spaced apart to permit the passage of unpopped corn but sufficiently close to prevent popped corn from passing therebetween and agitating devices operating between said bars for moving the popped corn longitudinally thereof and for discharging the same therefrom.

19. In a corn popping machine, the combination of a popping element, means for receiving the corn from said popping element and for separating the popped and unpopped corn, said means comprising a plurality of substantially horizontal bars spaced sufficiently close to prevent popped 60 corn from passing therebetween, toothed agitating bars operating between said first mentioned bars for moving the popped corn longitudinally thereof, crank arms whereon said agitating bars are mounted at their 65 ends, connections between said crank arms comprising additional crank arms at right angles thereto and a link connecting said additional crank arms.

20. In a corn popping machine, the combination of two popping elements, separating devices arranged to receive the corn from said popping elements and separate the unpopped corn therefrom, a common flavoring device arranged between said separating 80 devices and means for moving the popped corn in opposite directions from said separating devices to said common flavoring device.

21. In a corn popping machine, the combination of a popping element, a flavoring 85 trough, a spool-shaped member rotatably mounted in said trough and adapted to engage corn discharged from said popping element and a pair of fixed guide flanges arranged between the flanges of said spool-shaped member.

In testimony whereof I have signed my name to this specification in the presence of two subscribing witnesses.

NATHANIEL B. POST.
